UNITED STATES PATENT OFFICE.

JAMES H. DUGAN AND GEORGE MONCRIEF, OF STONEHAM, MASS.

IMPROVEMENT IN UMBRELLAS.

Specification forming part of Letters Patent No. **144,021**, dated October 28, 1873; application filed July 26, 1873.

To all whom it may concern:

Be it known that we, JAMES H. DUGAN and GEORGE MONCRIEF, of Stoneham, in the county of Middlesex and State of Massachusetts, have invented a new and useful Improvement in Umbrellas, of which the following is a specification:

Our invention consists of a simple, cheap, and efficient arrangement of an umbrella-top, so as to revolve upon the handle to relieve it when strong gusts of wind blow against it quartering, or when the top strikes against other umbrellas or other objects in crowded places. The said arrangement consists of a notched revolving ring for the ribs, between two collars on the handle, and a revolving notched ring on the runner, between two collars on it.

Figure 1 is a sectional elevation of the umbrella-frame, and Fig. 2 is a plan view of it.

The ribs A are jointed to the loose revolving collar B on the handle C, between the two

stationary collars D E, and the braces F jointed to a revolving ring, G, on the runner H, between the stationary collar I and the detachable collar J. The collar J screws onto the upper end of the runner to allow the ring to be put on and then secure it. The collar D is a flange of the tip K, which screws on the top of the handle after the collar B is put on and secures it.

Having thus described our invention, we claim as new and desire to secure by Letters Patent—

The rib and brace notch-pieces B and G, stationary collars D, E, I, and J, stem K, and runner H, all combined and arranged substantially as and for the purpose set forth.

JAMES H. DUGAN.
GEORGE MONCRIEF.
